UNITED STATES PATENT OFFICE

166,842

HEAD OF A DIAGNOSTIC INSTRUMENT

John T. Armbruster, Niagara Falls, N. Y., assignor to American Optical Company, Southbridge, Mass., a voluntary association of Massachusetts

Application September 7, 1951, Serial No. 16,578

Term of patent 14 years

(Cl. D57—1)

To all whom it may concern:

Be it known that I, John T. Armbruster, citizen of the United States of America, residing at Niagara Falls, in the county of Niagara and State of New York, have invented a new, original, and ornamental Design for the Head of a Diagnostic Instrument, of which the following is a specification, reference being made to the accompanying drawings, forming a part thereof.

In the drawing:

Fig. 1 is a front perspective view of a head for a diagnostic instrument, showing my new design;

Fig. 2 is a rear perspective view of the disclosure in Fig. 1; and

Fig. 3 is a side elevational view thereof.

The essential features of my design for a head for a diagnostic instrument are shown in full

lines, the fragments of the supporting pedestal shown in broken lines are for illustrative purposes only.

I claim:

The ornamental design for the head of a diagnostic instrument, substantially as shown and described.

JOHN T. ARMBRUSTER.
